UNITED STATES PATENT OFFICE.

ROBERT D. PASKETT, OF MOUNT VERNON, NEW YORK.

ANTISLIPPING OVERSHOE.

1,187,778.

Specification of Letters Patent. Patented June 20, 1916.

Application filed October 21, 1915. Serial No. 57,060.

To all whom it may concern:

Be it known that I, ROBERT D. PASKETT, a citizen of the United States, residing at Mount Vernon, in the county of Westchester and State of New York, have invented certain new and useful Improvements in Antislipping Overshoes; and I do declare the following to be a full, clear, and exact description of the invention, such as will enable others skilled in the art to which it appertains to make and use the same.

This invention relates to improvements in anti-slipping overshoes which are readily removable from the shoes of the wearer.

15 An important object of my invention is to provide a very simply constructed device of this character which, while being very efficient in operation, can be extremely inexpensively manufactured.

20 With the above general object in view my invention resides in certain novel features of construction, combination and arrangement of parts which will hereinafter be more particularly described and claimed.

25 In the accompanying drawings: Figure 1 is a perspective view of my improved overshoe; Fig. 2 is a central vertical longitudinal section thereof applied to a shoe shown in dotted lines; Figs. 3 and 4 are transverse vertical sections taken respectively on the lines 3—3 and 4—4 of Fig. 2.

In its preferred form my anti-slipping device comprises a sole member 1 which is cut to fit the shape of the shoe sole of the wearer 35 and is formed of any preferred flexible material, such as canvas, felt or the like. The forward or toe end of the member 1 is provided with a toe piece 2 adapted to receive the toe of the shoe of the wearer, while the 40 opposite end of the member 1 is provided with a heel piece 3 which is preferably formed integrally therewith, and is adapted to extend upwardly and partly surround the heel of the wearer.

45 The intermediate portions of the sole member 1 are provided on opposite sides, preferably adjacent the instep, with loops 4, each comprising a strip of flexible material bent upon itself intermediate its ends as 50 shown in the various figures of the drawings. The free ends of these loops 4 are secured one on each side of the upper and lower surfaces of the sole member as shown. The loops 4 are also preferably tapered from the inner toward their outer ends, and are adapted to extend up the sides of the shoe

of the wearer adjacent the instep portion of said shoe.

The upper end of the heel piece 3 has formed preferably integrally therewith a bifurcated tongue 5, the furcations 6 and 7 thereof being adapted to extend forwardly around the angle of the wearer and through the loops 4, one of said furcations being disposed on each side of the wearer's foot. 60 These members 6 and 7 constitute attaching straps by which the anti-slipping device may be securely held to the shoe of the wearer. These straps and also the loops 4 may be, if it is considered desirable, constructed of an elastic material. A suitable anti-slipping outer sole may be secured to the lower surface of the sole member 1. It is obvious that an outer sole need not be applied if the sole member 1 is constructed of 65 a material substantial enough to withstand considerable wear.

70 In applying the device the wearer inserts the toe of his shoe in the toe piece and then correctly positions the device with respect to the remainder of the shoe, the straps 6 and 7 being brought around to the forward portion of the wearer's foot and tied as shown, or attached by any other preferred means in order to secure the overshoe in operative 75 position.

80 From the foregoing description of the construction and operation of my improved anti-slipping overshoe it is obvious that I have produced a very simply constructed device which will readily accomplish the purposes for which it is designed.

85 I claim as my invention:

1. A device of the class described comprising a one piece sole member of flexible 95 material, a heel piece formed at one end thereof, a toe piece at the other, a pair of flexible loops secured to opposite sides of the sole member and fitting the instep of the wearer, and a pair of attaching straps secured to said heel piece, extended forwardly through said loops and adapted to be fastened over the wearer's instep.

100 2. A device of the class described comprising a one-piece sole member of flexible material, a heel piece formed at one end thereof, a toe piece at the other, a pair of flexible loops secured to opposite sides of the sole member and fitting the instep of the wearer, and a bifurcated tongue formed integrally 105 with the upper edge of said heel piece, the furcations thereof extending forwardly on

opposite sides of the shoe of the wearer and through said loops, whereby to provide attaching straps to be fastened over the wearer's instep.

5. 3. A device of the class described comprising a one-piece sole member of flexible material, a heel piece integrally formed therewith at one end, a pair of loops secured at opposite sides of the sole member, each 10 formed of a single piece of flexible material bent upon itself substantially in its middle, the free ends thereof being secured one on each face of the sole member, and a bifurcated tongue formed integrally with the 15 upper edge of said heel piece, the furcations thereof extending forwardly on opposite sides of the shoe of the wearer and through said loops whereby to provide attaching straps to be fastened over the wearer's instep.

4. A device of the class described comprising a one-piece sole member of flexible material and of a size to cover the sole of the wearer's shoe, a heel piece integrally formed

therewith at one end and covering the bottom of the heel of said shoe, a toe piece secured to said sole member to receive the toe of the shoe, a pair of loops attached at opposite sides of the sole members, each formed from a single piece of flexible material bent 30 upon itself in its middle, the free ends thereof being secured one on each face of the sole member, said loops extending upwardly and fitting the instep of the wearer, and a tongue formed integrally with the rear end of said 35 heel piece and extending up the back of the shoe, the upper end of said tongue being bifurcated, the furcations thereof extending forwardly on opposite sides of the wearer's shoe through said loops and adapted to be 40 fastened over the wearer's instep.

In testimony whereof I have hereunto set my hand in presence of two subscribing witnesses.

ROBERT D. PASKETT.
